UNITED STATES PATENT OFFICE

LOUIS G. KUNZER, OF OAK PARK, ILLINOIS

LOCOMOTIVE DRAFT INDUCER

Application filed August 1, 1927. Serial No. 209,742.

My invention relates to locomotive draft inducers for creating a draft while starting fires in locomotive boilers.

The principal object of the invention is 5 the production of an improved draft inducer for starting locomotive fires.

Another object is to produce a portable locomotive draft inducer operated by either steam or air.

10 Another object is to produce a locomotive draft inducer wherein the maximum efficiency is obtained with a minimum expenditure of steam, air or other fluid.

In a specific form of the invention, a self- 15 centering inverted cone is adapted to seat itself on the usual exhaust nozzle tip. The cone has a transverse pipe with a steam or air line connected therewith at one end thereof and an exhaust nipple or tip in the center 20 thereof for producing a draft of steam or air.

Other objects and features of the invention will become apparent from a consideration of the detailed description taken with 25 the accompanying drawings, wherein

Fig. 1 is a sectional view through the locomotive stack and smoke box showing the invention applied thereto;

Fig. 2 is a plan section along the line 2—2 30 of Fig. 1 looking in the direction of the arrows, and

Fig. 3 is a sectional view along the line 3—3 of Fig. 2.

In the accompanying drawings only 35 enough locomotive structure is shown to illustrate the manner of using the invention. The smoke box 10 has the front 11 of the flues communicating therewith through which the hot gases of the locomotive are 40 drawn and discharged through a stack 12 suitably positioned in the upper part of the smoke box. An exhaust nozzle 13 at the bottom of the smoke box is provided with an exhaust tip 14 through which steam from 45 the cylinders during the operation of a locomotive is discharged to induce a force draft through the flues in a manner well known to those acquainted with this art.

In most locomotives, a steam pipe runs 50 through the smoke box and has an exhaust

opening close to the exhaust nozzle so that when the locomotive is standing still, a draft may be induced by turning steam through this pipe. This pipe is known generally as the blower. In starting a fire in the locomotive, it is customary to blow live steam through this blower to facilitate the starting of the fires. My invention does away 55 with the use of the blower and induces a draft more economically and with a great deal less volume of steam or air.

My draft inducer comprises an inverted cone 16 having a pipe 17 disposed transversely in the base thereof with a discharge pipe 18 positioned at the center and an intake line 19 at one side. The intake line is adapted to extend up through the top of the stack and connect to a suitable hose connection (not shown) and it also serves as a handle whereby the cone may be seated with 60 in the top of the exhaust nozzle or be removed therefrom when the portable inducer is no longer required. Locomotives in which lignite coal is used have a bar 21 across the exhaust tip known as an exhaust tip bridge. 65 In order to permit the cone to be seated on this type of exhaust tip as well as on the standard type, I provide a vertical slot 22 into which the exhaust tip bridge extends 70 when the cone is placed in position.

The cone formation of the inducer permits the use thereof on all locomotives, the sloping sides of the cone compensating for differences of diameter of the exhaust tip. No matter what the size of the locomotive 85 or the exhaust tip, the discharge pipe will always be in the center, that is coinciding with the axis of the stack. This discharge pipe may be left open at the end but I have obtained the best results by employing a discharge tip 23 suitably secured to the end thereof and having a restricted passageway 24 in the center, so that a narrow stream of air of relatively high velocity is formed.

I have found that the distance of the discharge tip from the bottom of the stack 95 has a very great deal to do with the amount of draft induced for a given volume of air. Instead of attempting to determine the best position for each locomotive as it is fired, I 100

have adopted a standard length of discharge pipe which projects only a slight distance above the usual exhaust tip. In this way, I make use of the design of the locomotive, since obviously the exhaust tip of the locomotive will have been positioned a proper distance from the bottom of the stack.

Although the specific structure herein described, suits the purpose very well and is in fact the preferred of several forms which I have constructed while developing the invention, it is obvious that the objects may be accomplished by the employment of a different structure without departing from the spirit and scope of the invention. To secure the best results the portable discharge pipe or tip should be along the axis of the stack, and a sufficient distance below the same so that the greatest benefit in the fire box will result from the volume of fluid employed.

What I claim as new and desire to secure by United States Letters Patent is:

1. A portable draft inducer for the purpose described comprising an inverted cone, a pipe secured near the base of the cone transverse thereof and having its ends sealed, an exhaust tip connected to said transverse pipe at the center thereof and a supply pipe connected to said transverse pipe near the end thereof.

2. A portable draft inducer adapted to be used instead of the exhaust nozzle for inducing a draft while starting a fire in a locomotive boiler, said draft inducer including an inverted cone adapted to be seated on said exhaust nozzle, a discharge pipe projecting vertically from the center of the inverted cone and an intake pipe connected to the cone and communicating with the discharge pipe for supplying fluid pressure to said pipe and serving as a handle to insert the inducer through the top of a locomotive stack.

3. A portable draft inducer adapted to be used instead of the exhaust nozzle for inducing a draft while starting a fire in a locomotive boiler, said draft inducer including an inverted cone adapted to be seated on said exhaust nozzle, a discharge pipe projecting vertically from the center of the inverted cone and an intake pipe connected to the cone and communicating with the discharge pipe for supplying fluid pressure to said pipe and serving as a handle to insert the inducer through the top of a locomotive stack, a lower vertical slot being provided in the cone so that the inducer may be used to fire locomotives equipped with an exhaust tip bridge, the bridge extending into said vertical slot when the draft inducer is in position for use.

4. A portable draft inducer for use in lieu of the usual exhaust nozzle or blower to induce a draft in a locomotive fire box while

starting a fire therein, said draft inducer comprising an inverted cone adapted to be seated on the exhaust nozzle, a transverse pipe near the base thereof, a relatively long steam intake pipe connected to the transverse pipe for supplying steam thereto and also to serve as a handle for placing the inducer on the exhaust nozzle through the locomotive stack, a steam discharge pipe connected to the transverse pipe, and a discharge tip on said pipe.

5. A portable draft inducer designed to be inserted through a locomotive stack to take the place of the usual exhaust nozzle during preliminary firing of the locomotive, said draft inducer including an exhaust tip, means cooperating with the exhaust nozzle for supporting the exhaust tip substantially centrally positioned on said exhaust nozzle, and an intake line extending from said supporting means up through the locomotive stack when the exhaust tip is in position, so that said tip may be readily introduced and withdrawn through said stack.

In witness whereof, I hereunto subscribe my name this 2nd day of July, 1927.

LOUIS G. KUNZER.
